UNITED STATES PATENT OFFICE.

ALBION L. F. MITCHELL, OF LYNN, MASSACHUSETTS.

HEEL-TRIMMING MACHINE.

SPECIFICATION forming part of Letters Patent No. 363,410, dated May 24, 1887.

Application filed June 3, 1886. Serial No. 203,998. (No model.)

To all whom it may concern:

Be it known that I, ALBION L. F. MITCHELL, of Lynn, in the county of Essex and State of Massachusetts, have invented certain new and useful Improvements in Heel-Trimming Machines, of which the following is a specification.

This invention has for its object to provide an improved machine for automatically trimming heels of boots or shoes; and it consists, as a whole, in the combination of a rotary cutter-head, a jack adapted to oscillate, and provided with heel-clamping devices, also adapted to oscillate, a heel-pattern attached to the jack, so as to swing and oscillate with the heel to be trimmed, and a fixed rest, against which said pattern is pressed, the rest and pattern co-operating in governing the presentation of the heel to the cutter-head.

20 The invention also consists in certain details, all of which I will now proceed to describe.

Of the accompanying drawings, forming a part of this specification, Figure 1 represents 25 a front elevation of my improved machine. Fig. 2 represents an end elevation of the same. Figs. 2^a and 2^b represent, respectively, side and edge views of the bar and rack-segment whereby the heel-clamping devices are rocked 30 or oscillated. Fig. 3 represents a top view of the machine. Fig. 4 represents a section on line x x, Fig. 3. Fig. 5 represents a section on line y y, Fig. 3. Fig. 6 represents a section on line z z, Fig. 1, looking downwardly. Fig. 7 represents a view of a part of the opposite side of the machine from that shown in 35 Fig. 1.

The same letters of reference indicate the same parts in all the figures.

40 a represents the standard which supports the arbor b² of a rotary cutter-head, b, formed to trim a boot or shoe heel, as hereinafter described. To the standard a is rigidly attached a stout arm, c, and to the outer end of this arm is connected, by a pivot-bolt, d, a yoke or bearing, e, adapted to oscillate freely on the pivot d. An arbor, f, is journaled in the yoke or bearing e, and on said arbor is mounted the supporting-frame g of the jack, said frame having bearings h h, through which the arbor passes. The frame can therefore oscillate in 50 two directions—viz., with the yoke e and arbor

f on the pivot d, and independently of said yoke on the arbor f at right angles to the direction in which it is capable of oscillating on said pivot.

The boot or shoe holding portion of the jack is a rocking arbor, i², journaled in a bearing, g³, in the upper portion of the frame g and having an offset or bent portion, i³, and a sleeve or a tubular extension, i⁴, in line with the arbor i². The arbor i² is tubular, and in it is inserted a rod, i, having at one end a pivoted foot, i¹², which bears on the top of the heel portion of the last holding the boot or shoe. A nut, i⁵, having a hand-wheel, i⁶, is engaged with a flanged collar on the pinion h', as shown in Fig. 4, and engages with a threaded portion of the rod i, said rod being made adjustable lengthwise in the arbor i² by said nut, 70 so that it can be adjusted to different sizes of lasts. The sleeve i⁴ has a rod, i⁷, which has a plate, i⁸, at its inner end adapted to bear on the tread-surface of the heel, and is normally pressed against the latter by a spring, i⁹, in 75 said sleeve. A lever, i¹⁰, pivoted to the offset i³ and engaged with the rod i⁷, as shown in Fig. 4, enables the operator to throw the rod i⁷ back to release the heel. The rocking arbor and clamping devices above described are 80 rocked with the boot or shoe by means of a pinion, h', rigidly attached to the arbor i², and a rack-segment, i¹, on the upper end of the lever j', which is oscillated by an eccentric wrist-pin, m', on a disk on the arbor f, said pin entering 85 a slot in the lower end of the lever j'.

The described heel-clamping devices are so located with reference to the cutter-head b that the heel may be presented to said cutter-head. The oscillations of the frame g on the arbor f 90 enable the heel to move toward and from the cutter, and enable the frame g to move as required when the heel is rotating and is in contact with the wheel. The oscillations of the frame g and the yoke or bearing e on the pivot d enable the heel to be moved across the 95 perimeter of the cutter, so that all portions of the heel edge may be presented thereto.

P represents a heel-shaped pattern affixed to the offset i³ of the rocking arbor near the 100 tread-surface of the heel and surrounding the rod i⁷. Said pattern has the exact form which is to be imparted to the heel.

R represents a rest for said pattern attached

to the frame *a* and bearing against the molded surface of the pattern, so that the presentation of the heel to the cutter is determined by the pattern and rest, the latter governing the approach of the heel toward the cutter, caused by the oscillations of the frame *g* on the arbor *f*, and causing the frame *g* to move in a curved path corresponding to the curvature to be given to the heel from bottom to top. The rest *R* is adjustable, so that it may project more or less from the frame *a*, according to the size of the heel-pattern, and is provided with a threaded shank, *R'*, Fig. 5, which is engaged by a nut, *R''*, which is free to rotate on said shank, but is confined between two parts of a U-shaped bracket, *R'*. By rotating said nut the rest *R* may be moved in or out, as will be readily seen.

The pattern is attached by a screw to an arm, *l'*, which is secured by a screw, *l''*, to a plate, *l''*. Said plate is secured by a screw, *l''*, to the offset portion *i'* of the rocking arbor, and may be turned on the screw *l''* when the latter is loosened. The screw *l''* is located at one side of the screw *l'*, so that when the plate *l''* is turned the position of the arm *l'* will be varied, so that said arm and the heel-pattern thereon may be inclined either toward the right or toward the left, as may be required to cause it to conform to heels on right or left boots. The arm *l'* has a slot through which the screw *l''* passes, said slot being necessary to permit the described turning of the plate *l''* to vary the inclination of the pattern.

The frame *g* is connected to the standard by a sliding telescopic connection—viz., a socket, *w*, pivotally connected to a sleeve, *w'*, which is fitted to slide on a curved guide-rod, *u*, rigidly attached to the standard *a*, and a rod, *a'*, secured to the frame *g* and sliding into and out of the socket *w*. A spring, *f'*, secured at one end to the frame *g* and at the other end to a fixed support, pulls the frame toward the cutter-head.

I have provided means whereby the frame *g* is moved automatically in the direction required to first present the lower or top-lift edge of the heel to the cutter and cause the cutting action to progress gradually to the heel-seat portion, and is then released, so that the operator can swing it in the opposite direction to the starting-point. Said means consist of an arbor, *A*, journaled in the frame *g*, and having at one end a disk, *B*, and at the other end a mutilated worm-wheel, *C*, a connecting-rod, *D*, eccentrically pivoted at one end to a wrist-pin on the disk *B*, and pivoted at the other end to the socket *w*, an arbor, *E*, journaled in bearings on the frame *g*, and arranged at right angles to the arbor *A*, and a worm, *F*, on said arbor, meshing with the worm-wheel *C*. The arbor *E* is provided with a series of pulleys, *H*, of different diameters, one of which is connected by a belt, *J*, to one of a similar series of pulleys, *I*, on the arbor *f*. The rotation thus imparted to the arbor *E* is communicated by the worm *F* and worm-wheel

C to the arbor *A*, and the eccentric wrist-pin *L* is thus caused to act on the connecting-rod *D* so as to swing the frame *g* in the direction indicated by the arrow in Fig. 1, thus causing the heel to move across the cutter-head in the manner required to present all parts of its edge to the cutter. The length of the oscillating movements thus imparted to the frame *g* may be varied by adjusting the wrist-pin *L* toward or from the center of the disk *B*, a slot being provided in the disk, in which the wrist-pin is adjustable. When the toothless portion of the wheel *C* reaches the worm *F*, the last-described movement of the frame ceases, and the frame remains at rest until moved to its starting position by the operator.

The rapidity of the described swinging movements of the frame may be varied by means of the different-sized pulleys *H* and *I*.

I prefer to make the rod *j'*, having the rack-segment *i'*, in two parts, 2 3, pivotally connected at 4. (See Figs. 2^a and 2^b). The part 2 has the rack-segment *i'*, and also has two ears, 90 in which is journaled a worm, 5, meshing with teeth 6 formed on the upper end of the part 3. By rotating said worm the part 2 may be turned so as to move the rack-segment longitudinally in either direction. I am thus enabled to regulate the limits of the oscillating movements imparted to the jack by the rod *j'* and its rack-segment.

It will be observed that the jack shown and described in this application is similar in certain respects to that shown in Letters Patent of the United States, granted to me February 17, 1885, No. 312,573. I do not therefore here claim anything shown in said patent.

I claim—

1. The combination, with the rotary cutter-head, of the jack pivoted to swing universally, as described, and provided with oscillatory heel-clamping devices, automatic mechanism, substantially as described, whereby said clamping devices may be oscillated while the heel held thereby is being presented to the cutter-head, mechanism, substantially as described, whereby the jack is automatically moved to cause the heel to move progressively across the cutter-head, a heel-pattern affixed to the jack, whereby the direction of the progressive movement of the jack is determined, and a rest for said pattern, as set forth.

2. The combination of a supporting-standard, a rotary cutter-head mounted thereon, a frame pivoted to said standard to swing universally, heel-clamping devices, substantially as described, mounted in the swinging end of said frame, a heel-pattern affixed to said frame, mechanism whereby said heel-clamping devices are oscillated, mechanism whereby the frame is moved automatically in one direction to cause the heel to move progressively across the cutter-head, and then released to permit its movement by the operator in the opposite direction, and a rest for the heel-pattern, all arranged and operating substantially as set forth.

3. The combination of a supporting-stand-
ard, a rotary cutter-head mounted thereon, a
frame, *g*, pivoted to said standard to swing
universally, heel-clamping devices, substan-
tially as described, mounted in the swinging
end of said frame, a heel-pattern also mounted
on the swinging end of the frame, mechanism,
substantially as described, whereby said heel-
clamping devices and pattern are oscillated,
10 the rest *R* for said pattern, the socket *w*,
mounted to slide on a guide on the supporting-
standard, the rotating arbor *A*, journaled in
the frame *g*, and the connecting-rod *D*, con-
nected to the socket *w* and to a disk on the ar-
bor *A*, as set forth.
- 15 4. The combination of the swinging and
rocking jack, the heel-pattern affixed to the
jack, means, substantially as described, for
swinging the jack, the rotary cutter, the ad-
20 justable rest, and means, substantially as de-
- scribed, for holding the rest in the different
positions to which it may be adjusted, as set
forth.
5. The combination of the jack having the
rocking arbor *i*², and its heel-clamping devices, ²⁵
the oscillating rod *j*', composed of the sections
2 3, the former having the rack-segment mesh-
ing with a pinion on said arbor, said sections
being pivotally connected, and means, substan-
tially as described, for rigidly connecting the ³⁰
section 2 to the section 3 in different positions,
as set forth.

In testimony whereof I have signed my name
to this specification, in the presence of two sub-
scribing witnesses, this 29th day of May, 1886. 35
